UNITED STATES PATENT OFFICE.

HEINRICH A. W. PETERSEN, OF GARY, INDIANA.

REFRIGERATOR.

Application filed December 19, 1923. Serial No. 681,548.

This invention relates to a refrigerator and more particularly to a refrigerator which is provided with a vacuum casing.

One of the objects of the present invention is to provide a highly efficient and economical refrigerator.

A further object of the invention is to provide an improved door construction for a refrigerator.

10 A still further object of the invention is to provide a refrigerator construction by means of which the ice chamber is excluded from communication with the outside air when the refrigerator door is open.

15 A still further object of the invention is to provide a novel or improved shelf construction for a refrigerator.

These and other objects are obtained by providing a construction and arrangement 20 of the various parts in the manner herein-after described and particularly pointed out in the appended claims.

Referring to the drawings, Fig. 1 is a front elevational view showing my improved refrigerator.

Fig. 2 is a cross sectional view taken on a plane passing through the longitudinal axis of the refrigerator.

25 Fig. 3 is a cross sectional view taken on the lines 3—3 in Fig. 2.

Fig. 4 is a top plan view with certain of the parts eliminated for the purpose of showing the manner in which my improved disappearing door is eccentrically mounted 35 with respect to the longitudinal axis of the refrigerator, and

Fig. 5 is a perspective view of my improved door.

For the purpose of illustration I have 40 shown my improved vacuum refrigerator comprising a base 10 provided with a bottom 11.

This base 10 is cylindrical in form and is provided with an opening 12 on one side 45 thereof through which a drip pan 13 may be inserted or removed. Securely mounted on the base 10 and preferably by bolts 14 is a cylindrical casing 15. This casing 15 is provided with an outer and inner wall 16 and 17 between which is formed a vacuum chamber 18, thus providing a construction 50 which will reduce to a minimum the radiation of heat through the walls thereof. The outer wall 16 and the inner wall 17 extend 55 inwardly as shown at 19 and 20 to form the bottom of the refrigerator proper. The

walls 19 and 20 are connected centrally of the refrigerator in such a manner as to form a centrally disposed aperture 21 through which a drain pipe 22 extends. 60 The drain pipe 22 is supported in this aperture by a bracket 23 which is rigidly secured to the pipe in any well known manner. Removably mounted on the cylindrical casing 10 is a cover 24. The cover 24 is 65 preferably made of a two-wall construction, as shown at 25 and 26 having a vacuum chamber 27 therebetween. The cover 24 is provided with a peripherally arranged recess 28 which is adapted to seat itself on the 70 curved portion 29 of the cylindrical shell or casing 15. This construction permits an air tight connection between the cover 24 and the casing 15 of the refrigerator. However, if it is found necessary, suitable hinges may 75 be provided for hingedly connecting the cover to the casing of the refrigerator.

In carrying out my improved ice box construction I have provided an ice chamber in the upper portion thereof by securing a circular disc 30 to the inner walls 17 of the casing. The disc 30 is provided with a centrally disposed enlarged aperture 31 for the purpose hereinafter set forth. The upper end of the drain pipe 22 as shown at 32' is 80 supported in its position by a horizontally disposed plate or disc 32 which is secured to the inner walls 17 of the casing 15 in any well known manner. This plate or disc 32 is provided with a semi-circular opening 33, as 85 shown in Fig. 3. The upper end of the pipe 22 has secured thereto a circular tray 34 in such a manner that the cool air may pass through the opening 31 and outwardly from 90 the tray 34 down through the semi-circular opening 33 in the disc 32 to the other compartments of the refrigerator. The tray 34 is provided with a peripherally arranged 95 and upwardly extending flange 35 which retains the drippings from the ice for conveying the same into the drain pipe 22. Loosely mounted on the tray 34 is an ice rack 36 for supporting the ice in position in the refrigerator. In order to divide the compartments below the ice chamber I have provided 100 a novel form or rotatably mounted shelves 37. Each of these shelves are spaced at the desired intervals and are maintained at these intervals by collars 38, which are secured to the drain pipe 22 in any well known manner. By this arrangement it will be

understood that each of the trays may be revolved so that easy access to any portion of them may be easily had.

Another important feature of my refrigerator is the provision of a disappearing door, which, when in its open position closes the communication between the ice chamber and the other compartments of the refrigerator. This construction comprises a semi-cylindrical shell 39 which is preferably formed of two walls having a vacuum chamber therebetween, as shown at 40. The upper end of the semi-cylindrical shell is provided with a semi-circular disc, as shown at 41. This semi-circular disc is secured to the shell in any well known manner and is provided with an aperture 42 disposed concentrically with relation to the longitudinal axis of the semi-circular shell. The lower end of the semi-cylindrical shell is provided with a spider-like support 43 having the outer ends of its arms, as shown at 44, secured to said shell. The spider 43 is provided with a centrally disposed bore 45 which is positioned concentrically with the aperture 42 of the semi-circular disc 41. The door 39 is pivotally mounted on the drain pipe 22 by having the pipe 22 extend through the aperture 42 of the semi-circular disc 41 and through the aperture 45 of the spider 43. In order to eliminate all friction in operating the door I have provided a ball bearing 46, which is positioned between the bearing portion 47 of the spider 43 and the bracket 23 of the refrigerator. In order to further eliminate any friction and to secure the sides of the door, when in its closed position, against admission of warm air into the refrigerator, the drain pipe 22 is positioned eccentrically with respect to the longitudinal axis of the cylindrical casing 16, as clearly shown in Fig. 4. It will of course be understood that the opening in the casing 15 normally covered by the door extends substantially around one half the refrigerator, as clearly shown in Figs. 1 and 4. To further insure against admission of warm air into the refrigerator, when the door is closed, I have provided a felt strip adjacent the top and bottom of the door, as shown at 48, which is engageable with a corresponding brass strip on the inner side of the refrigerator which contacts throughout with the felt strip when the door is closed. The door 39 is limited in its oscillatory movement about its pivot on the drain pipe 22 by a stop 49 secured on the inside of the refrigerator. The lower end of the drain pipe 22 is provided with a U-shaped trap 50, which retains water in the bottom thereof and prevents the admission of warm air into the ice chamber.

In the operation of the above described device, it will of course be understood that the ice 51 is placed in the ice chamber where

it rests upon the tray 30 and rack 36. As the ice melts the cooling air passing through the rack over the sides 35 of the tray 34 and downwardly through the semi-circular opening 33 of the disc 32 into the lower compartment of the refrigerator. When it is desired to have access to the compartments below the ice chamber, the door is swung about its pivots 42 and 45 on the drain pipe 22 until the door has practically disappeared where it occupies the position shown in the dotted lines in Fig. 4. When in this position the semi-circular disc 41 of the door 39 covers substantially the circular opening 33 in the disc 32 so that the communication between the ice chamber and the compartments therebelow is shut off, thereby preventing the warm air from entering the ice chamber of the refrigerator and thereby conserving the ice.

It will be seen by referring to Fig. 4 that by positioning the pivot of the door 39 eccentrically with respect to the longitudinal axis of the cylindrical casing 15 the door is not only given greater clearance between the inner wall of the casing when opened, but this arrangement also insures the door opening in the casing to be air tight when the door is closed.

It will be further noted that by providing the rotatable shelves 37 it is not necessary to open the door to its extreme position in order to have easy access to the articles on the tray. In other words the door may be partially opened and the shelves 37 may be revolved so that an article on any portion of the shelves may be easily removed.

While in the above specification I have described one embodiment which my invention may assume in practice, it will of course be understood that the same is capable of modification, and that modification may be made without departing from the spirit and scope of the invention as expressed in the following claims.

What I claim as my invention and desire to secure by Letters Patent is:

1. A refrigerator comprising a base, a refrigerator casing mounted on said base, a disappearing arcuately shaped revolving door operatively mounted on said casing, and means adapted to revolve with said door whereby communication between certain portions of said refrigerator and certain other portions thereof is cut off when said door is opened.

2. A refrigerator comprising a base, a vacuum refrigerator casing mounted on said base, a disappearing arcuately shaped door pivoted eccentrically with respect to the longitudinal axis of said casing and a plurality of shelves pivoted concentrically with said door.

3. A refrigerator comprising a base, a vacuum cylindrical casing mounted on said

- base, and a door pivoted eccentrically with respect to the longitudinal axis of said casing.
4. A refrigerator comprising a base, a casing mounted on said base, said casing divided into a plurality of compartments in communication with each other, a disappearing arcuately shaped door pivotally related to said casing and means whereby the communication between certain of said compartments is cut off when the door is opened.
5. A refrigerator comprising a cylindrical casing, a drain pipe mounted substantially in the longitudinal center of said casing, a door pivoted to said drain pipe, and a plurality of shelves rotatably mounted concentrically with the pivot of said door.
6. A refrigerator comprising a cylindrical casing, a drain pipe mounted substantially in the longitudinal center of said casing, said casing having an opening in one side thereof, and a disappearing door pivotally connected to said drain pipe to cover said opening.
7. A refrigerator comprising a cylindrical casing, a door pivoted eccentrically with respect to the longitudinal axis of said casing, and a shelf rotatably mounted in said casing concentrically with respect to the pivot of said door.
8. A refrigerator comprising a cylindrical casing, a door pivoted eccentrically with respect to the longitudinal axis of said casing, and a plurality of shelves rotatably mounted in said casing concentrically with respect to the pivot of said door.
9. A refrigerator comprising a cylindrical casing, having an opening on one side thereof, an ice chamber in the upper portion of said casing, a drain pipe mounted in said casing for draining water from said ice chamber, and a door pivotally mounted on said drain pipe for covering the opening in said casing.
10. A refrigerator comprising a cylindrical casing, having an opening on one side thereof, an ice chamber in the upper portion of said casing, a drain pipe mounted in said casing for draining water from said ice chamber, a plurality of shelves rotatably mounted on said drain pipe, and a door pivotally mounted on said drain pipe for covering the opening in said casing.
11. A refrigerator comprising a cylindrical casing having an opening in one side thereof, and a disappearing door pivotally connected to said casing eccentrically with respect to the longitudinal axis of said casing for covering said opening.
12. A refrigerator comprising a cylindrical casing, having an opening on one side thereof, an ice chamber in the upper portion of said casing, a drain pipe mounted in said casing for draining water from the ice chamber, a door pivotally mounted on said drain pipe for covering the opening in said casing and means whereby the communication between said ice chamber and the other portions of said casing is shut off when the door is opened.
13. A refrigerator comprising a cylindrical casing, having an opening on one side thereof, an ice chamber in the upper portion of said casing, a drain pipe mounted in said casing for draining water from the ice chamber, a plurality of shelves rotatably mounted on said drain pipe, a door pivotally mounted on said drain pipe for covering the opening in said casing and means whereby the communication between said ice chamber and the other portions of said casing is shut off when the door is opened.

In testimony whereof I have signed my name to this specification on this 11th day of December A. D. 1923.

HEINRICH A. W. PETERSEN.
